G. E. WILLIAMS

STEAM HEATED PRESS FOR SHAPING WIPER CLOTHS

Filed April 23, 1923

Fig. 3.

INVENTOR.
GEORGE E. WILLIAMS.

BY HIS ATTORNEY.

James F. Williamson

UNITED STATES PATENT OFFICE.

GEORGE E. WILLIAMS, OF MINNEAPOLIS, MINNESOTA.

STEAM-HEATED PRESS FOR SHAPING WIPER CLOTHS.

Application filed April 23, 1923. Serial No. 634,201.

To all whom it may concern:

Be it known that I, GEORGE E. WILLIAMS, a citizen of the United States, residing at Minneapolis, in the county of Hennepin and State of Minnesota, have invented certain new and useful Improvements in Steam-Heated Presses for Shaping Wiper Cloths; and I do hereby declare the following to be a full, clear, and exact description of the invention, such as will enable others skilled in the art to which it appertains to make and use the same.

This invention relates to a shaping device in the form of a press, and while the invention is applicable to other uses, the same has preferably been designed to shape a novel form of wiper cloth. Such a cloth is used in forming and shaping wiped joints on lead pipe and are given a permanent shape by being placed under pressure while heat is simultaneously applied thereto.

It is an object of this invention to provide a device of simple and efficient form having hollow forms with co-operating curved or semi-cylindrical surfaces, between which the article is pressed, said forms being adapted to have a heating medium supplied thereto.

It is a further object of the invention to provide such a device having a lower hollow form with base forming means thereon, which means carry upstanding guides between which an upper form is guided and operating means for said latter form being provided in the shape of a screw journaled in the lower form and engaging the upper form as a nut.

These and other objects and advantages of the invention will be fully set forth in the following description made in connection with the accompanying drawings, in which like reference characters refer to the same parts throughout the different views, and in which,

Fig. 1 is a view in front elevation of the device;

Fig. 2 is a plan view thereof; and

Fig. 3 is a vertical section taken on the line 3—3 of Fig. 1, as indicated by the arrows.

Referring to the drawings, the device comprises a lower form 1 illustrated as of semi-cylindrical shape and as having an upper convex curved or semi-cylindrical surface. The form 1 is hollow and a pipe 2 ex-

tends into one end thereof which is adapted to supply steam from any suitable source, while a pipe 3 extends from the other end of the form and acts as an exhaust or drain pipe. The form 1 has secured thereto at its ends base flanges 4 preferably formed integrally therewith. The flanges 4 are illustrated as of general rectangular form extending transversely of the ends of the form 1 and are equipped with holes 5 adapted to receive suitable securing bolts by which the members may be firmly secured to any convenient base. The members 4 have guide members 6 extending upwardly therefrom which are shown as in the form of T-shaped ribs, from the cross web of which projects inwardly a rectangular rib 7. Another form 8 is provided having slots at its ends fitting over the ribs 7 so as to be guided thereby in its vertical movement. The form 8 has a concave surface 9 on its underside adapted to fit over the upper surface of form 1 and is shown as having curved parallel semi-annular walls and constituting a hollow member. Pipe 10, which will be connected with some suitable source of steam supply, extends into the form 8 at one end and another pipe 11 which will form an exhaust or drain pipe extends into the form at its other end at the opposite side thereof. The form 1 has a central hub portion provided with a shouldered aperture in which is journaled the lower end of a screw member 12, said screw having a collar at its lower end fitting in the shouldered part of the aperture in the member 1. A plate 13, preferably, is secured to the bottom of the form 1 beneath the screw 12. The screw 12 extends upwardly and engages in a threaded hub 14 formed in the form 8, which hub 14 acts as a nut. The screw is provided at its upper end with an operating hand wheel 15 by which it is turned relatively to move the forms 1 and 8.

In operation, the wiper cloths are placed on the form 1 with the center line of the cloth in alignment with the longitudinal center line of the form. The forms will be supplied with steam so as to be heated and when the cloths are in position, as stated, the hand wheel 15 will be turned and the form 8 moved down into contact with the cloths which will then be pressed between the forms and given a curved shape similar thereto. The cloths are left in the press for

a suitable time and are then removed. After being so treated they retain their curved shape.

From the above description it is seen that 5 applicant has provided a simple and convenient means for shaping the wiper cloths. Quite a large number of the cloths can be placed in the device at one time so that the work will be rapidly performed.

10 It will, of course, be understood, that various changes may be made in the form, details, arrangement and proportions of the parts without departing from the scope of applicant's invention, which, generally 15 stated, consists in a device capable of carrying out the objects above enumerated and such as shown and described and set forth in the appended claims.

What is claimed is:

20 1. A device for shaping wiper cloths comprising an elongated form substantially semi-cylindrical in cross section and having a convex upper surface and a flat base member at each end thereof adapted to be attached to a support, standards rising vertically from said base members having vertical ribs projecting therefrom, said form having a hub at its central portion provided with a central bore having an enlarged lower 25 portion, a screw journaled in said bore having a head seated in said enlarged portion thereof, a plate secured to the bottom of said hub holding said screw in place, said

screw having a hand wheel at its top, an elongated form disposed above said form 35 having a concave lower surface adapted to fit over said first mentioned form and having lugs at each end embracing and slidable on said ribs, said last mentioned form having a central hub forming a nut in which 40 said screw travels, and means for supplying steam to said form.

2. A device for shaping wiper cloths and other articles comprising an elongated hollow form having a concave semi-cylindrical upper surface thereon, means for supplying steam to the inside of said form, base members secured to the ends of said form, upright guide members having vertical slots therein secured to said base members, an 50 elongated hollow form having a concave lower surface adapted to fit over the said surface on the first mentioned form, and having guide means at each end thereof, movable in said slots, means for supplying 55 steam to said last mentioned form, a screw rotatably secured in said first mentioned form and engaging said last mentioned form as a nut, said screw being disposed centrally of said forms and having means 60 thereon for turning the same to move said forms together to shape the wiper cloth between the said surfaces thereof.

In testimony whereof I affix my signature.

GEORGE E. WILLIAMS.
